RAZOR

Winfred T. Parkin, Providence, R. I., assignor to
 Theodore W. Foster & Bro. Co., Providence,
 R. I., a corporation of Maine

Application June 1, 1935, Serial No. 24,508

15 Claims.

(Cl. 30—46)

This invention relates to improved safety razors, particularly of the type employing reciprocating blades, and to blades to be employed in such razors. In some respects the present invention affords an improvement upon the type of razor disclosed in United States Letters Patent No. 1,890,733 to John L. King.

In accordance with the present invention, however, an actuating roller, for example having a cam groove, may be arranged directly to engage a portion or portions of a reciprocating blade so that only one moving part is necessary to impart a reciprocating movement to the blade; thus sliding saddles, actuating plates, oscillating rods and the like are avoided. This construction also permits the provision of a blade with two cutting edges with the driving roller symmetrically arranged relative to the blade and these edges. Furthermore, the actuating roller itself may be disposed with its axis of rotation in the region 10 of the plane of the blade, so that the exposed portion of the roller does not protrude unduly above the retainer or cap of the holder. Accordingly, a holder may be provided which may have a compact, flat form comparable to that provided 15 by holders which are not supplied with reciprocating blades.

An important aspect of the invention involves the form of the blade support which may be made of a single piece of sheet metal to provide 20 an opening and recess to receive the lower part of the actuating roller and to provide ears in which the ends of the roller are journaled. The support may, for example, have a rectangular opening or recess with struck-up ears at its ends, 25 while the metal at the intermediate part of the opening is pressed downwardly to afford two generally semi-cylindrical sleeve elements that may enclose portions of the roller and an intermediate cylindrical boss integral with these 30 elements to receive the handle. The boss and elements cooperate in providing a stiff reinforcement for the portion of the support which is connected to the handle despite the provision of the opening to receive the roller. The retainer, 35 which may conveniently be of the swinging type, may be arranged to provide an opening through which the upper surface of the roller is exposed 40 for engagement with the flesh of the user of the razor.

A razor of this type may employ a blade of simple form having a generally rectangular opening therein, the sides of which may engage the edges of the ears which support the actuating roller, thus the blade is constrained to follow a

straight-line reciprocatory path. Integral tabs or ears may extend inwardly from the sides of the rectangular opening in the blade to afford follower elements which engage opposite sides of the roller. Thus the roller may be provided with a cam groove engaging ears on the blade at both sides thereof, and balanced forces tending to reciprocate the blade are imposed upon both sides thereof. Furthermore, the blade may be of symmetrical design so that either face thereof may 10 be disposed uppermost in the razor.

A further advantageous feature of the invention pertains to the arrangement of the parts, and especially the cam groove of the roller and the cooperating parts of the blade so that the 15 latter may readily be located in operating position upon the support without necessity for careful adjustment.

In the accompanying drawing:

Fig. 1 is a central vertical section of the blade holder of a razor embodying the parts of this invention, certain parts, including the upper part 20 of the handle, being shown in elevation;

Fig. 2 is a central section on a plane at right angles to that of Fig. 1;

Fig. 3 is a plan view of the holder with the roller 25 removed, showing the retainer swung to its open position;

Fig. 4 is a similar view, but showing the roller and blade, and with a part of the retainer broken away;

Fig. 5 is a plan view of a blade which may be employed in a razor of the present type;

Fig. 6 is a section indicated by line 6—6 of Fig. 1; and

Fig. 7 is a section indicated by line 7—7 of Fig. 3.

In the accompanying drawing, which illustrates the principles of the present invention, the handle of the razor is designated by numeral 1. The upper end of the handle fits tightly within an integral boss 2 of the blade support 3, which forms a part of the blade holder. The support may be provided with a plurality of elongate recesses 4 which separate its body portion from rail-like guard portions 5. The support may also have a 45 plurality of small protuberances 7 (Fig. 3) disposed adjoining the openings 4 to engage the lower surface of the blade and support the same.

The support 3 is provided with a central generally rectangular opening 10, the intermediate 50 parts of the sides of which are bulged slightly to conform to the curvature of boss 2. The metal at the ends of the opening 10 is struck upwardly to afford small ears 15 which have openings in

which the ends of an actuating roller 17 are journaled. This roller is provided with roughened or fluted end portions 18 and an intermediate part providing a cam groove 19. Below the intermediate part of the opening 18, and at each side of the boss 2, the metal of the support 3 is bent into a substantially semi-cylindrical form to afford guard sleeve elements 20 (Figs. 6 and 7) which surround the adjoining parts of the roller 17. The elements 20 are integral with the boss 2 and in effect afford a recess beneath the central part of opening 18 in which the lower part of the roller is received. Obviously the elements 20 and the boss 2 cooperate in reinforcing the guard in the region of the opening 18 and afford a rigid structure where the guard or support is connected to the handle.

The holder may also include a retainer 25 which is connected by a suitable hinge 21 to one end of the support 3. The opposite end of the retainer is provided with a resilient clip 22 which may normally engage the lower surface of the supporting plate adjoining a notch 23 in the end of that plate. When the clip 22 is pressed upwardly 25 and outwardly, the retainer may be swung to the open position shown in Fig. 3, thus exposing the surface of the support so that a blade may be disposed therein. The retainer is also provided with a central generally rectangular opening 28 in 30 which the upper part of the roller 17 is received. The ends of this opening are provided with notches 29 in which the edges of the ears 15 may be received, the upper surfaces of the latter being disposed substantially in the region of the upper 35 surface of the retainer, as shown in Fig. 1.

The blade 40 may be of generally rectangular form, as shown in Fig. 5, having parallel cutting edges 41 and a central opening 42. This opening may be of generally rectangular form, having 40 straight parallel sides 43 to slide in juxtaposition to the edges of the ears 15 (Figs. 4 and 6). The intermediate portions of the sides 43 of the opening are, however, provided with inwardly extending follower tabs or lugs 46 which are received in 45 the cam groove 19. These ears may have straight edges to engage the sides of the groove and curved ends to facilitate their initial engagement with the groove.

When a blade of this type is to be disposed in the razor, the retainer 25 is swung to its open 50 position illustrated in Fig. 3, and the blade is moved downwardly so that the tabs 46 engage the cam groove 19, the curved ends of these ears readily moving into initial engagement with the 55 cam groove. The blade is then moved downwardly so that the ends of opening 42 fit about the ears 15 and the sides 43 of the opening are in sliding engagement with the edges of the ears. The retainer 25 may then be swung to its normal 60 position so that the upper part of the roller extends through the opening 28 in the retainer. When the razor is used, the roughened portions 18 of the roller 17 engage the flesh of the user, reciprocating the blade and acting through the 65 cam groove 19 and follower lugs 46 in imparting a reciprocating movement to the blade, which is restrained to follow a straight-line path by the ears 15.

It is evident that this invention affords a very 70 simple arrangement wherein a driving roller is the only moving part necessary to impart movement to a reciprocating blade, the ears which support the roller forming guide means to restrain the blade so that it follows a straight-line path.

75 The structural arrangement illustrated herein

permits a blade support to be formed of a single piece of sheet metal not only to provide guard rails and a boss portion to receive the end of the handle, but also to provide the guard sleeve elements 20 below the roller, these elements also connecting the opposite sides of the opening 18 and affording a reinforcement for this portion of the holder; furthermore, the ears which support the actuating roller and which afford guide means for the reciprocating blade may also be integral with the supporting blade. Due to the arrangement of the axis of the roller in the region of the plane of the blade, an unusually compact construction is provided so that the exposed portion of the roller does not extend substantially above the retaining plate. Thus neatness of appearance is afforded and convenience in shaving is facilitated.

It should be understood that the present disclosure is for the purpose of illustration only and 20 that this invention includes all modifications and equivalents which fall within the scope of the appended claims.

I claim:

1. A razor of the class described comprising a 25 blade support, a blade, a retainer normally co-operating with the support in holding the blade in place, an actuating roller rotatably mounted on the support and having its axis of rotation near the plane of the blade, the retainer having an 30 opening through which the upper portion of the roller is exposed for engagement with the flesh of the user of the razor, said roller having a cam portion, said blade having an integral part engaging said cam portion and functioning as a 35 follower so that the blade is reciprocated as the roller is rotated.

2. A razor of the class described comprising a 40 blade support, a blade, a retainer cooperating with the support in holding the blade in place, said support having upstanding elements extending into an opening in the blade and affording guide means therefor to restrain the blade to follow a straight-line path, an actuating roller rotatably mounted on said elements and providing a cam 45 portion, a part of the blade engaging said cam portion and functioning as a follower therefor so that the blade is reciprocated in response to rotation of the roller.

3. A razor of the class described comprising a 50 blade support, a blade, a retainer cooperating with the support in holding the blade in place, said support having a central opening and upstanding integral ears at the ends of the opening, the blade having an opening with its sides 55 slidably engaging the edges of said ears so that the blade is constrained to follow a straight-line path, an actuating roller journaled in openings in said ears and having a cam portion, portions of the blade extending inwardly from the opposite 60 sides of its opening and engaging said cam portion to function as followers therefor so that the blade is reciprocated in response to rotation of the roller.

4. A razor of the class described comprising a 65 blade support, a blade, a retainer cooperating with the support in holding the blade in place, said support having a central opening and upstanding integral ears at the ends of the opening, the blade having an opening with parallel sides 70 slidably engaging the edges of said ears so that the blade is constrained to follow a straight-line path, an actuating roller journaled in openings in said ears and having a cam portion, portions 75

of the blade extending inwardly from the sides of its opening and engaging said cam portion to function as followers therefor, integral portions of said support being of substantially semi-cylindrical form and being disposed adjoining the central part of the opening in the support to afford shields for the lower part of the roller while connecting the portions of the support at opposite sides of the opening therein.

10. 5. A razor of the class described comprising a blade support, a blade, a retainer cooperating with the support in holding the blade in place, said support having a central opening and upstanding integral ears at the ends of the opening, the blade having an opening with parallel sides slidably engaging the edges of said ears so that the blade is constrained to follow a straight-line path, an actuating roller journaled in openings in said ears and having a cam portion, portions 20 of the blade extending inwardly from the sides of its opening and engaging said cam portion to function as followers therefor, integral portions of said support being of substantially semi-cylindrical form and disposed adjoining the central 25 part of the opening in the support while connecting the portions of the support at opposite sides of the opening therein, a portion of said support providing a central boss for connection to a handle, said integral portions being integrally connected to said boss.

6. A razor of the class described comprising a blade support, a blade having an opening with parallel sides, a retainer cooperating with the support in holding the blade in place, said support having upstanding ears extending through the opening in the blade, the parallel sides of said opening slidably engaging the edges of said ears so that the latter afford guide means to constrain the blade to follow a straight-line path, an actuating roller having its ends journaled on said ears and providing a cam portion, the roller having its axis of rotation disposed adjoining the plane of the blade, the retainer having an opening through which the upper part of said roller is exposed, a part of the blade engaging said cam portion and functioning as a follower therefor so that the blade is reciprocated in response to rotation of the roller.

7. A razor of the class described comprising a blade support, a blade having an opening with parallel sides, a retainer cooperating with the support in holding the blade in place, said support having upstanding ears extending through the opening in the blade, the parallel sides of said opening slidably engaging the edges of said ears so that the latter afford guide means to constrain the blade to follow a straight-line path, an actuating roller having its ends journaled on said ears and providing a cam portion, the roller having its axis of rotation disposed adjoining the plane of the blade, the retainer having an opening through which the upper part of said roller is exposed, integral projections of the blade extending inwardly from the parallel sides of its opening and engaging said cam portion, said projections functioning as followers so that the blade is reciprocated in response to rotation of the roller.

8. A razor of the class described comprising a blade support, a blade having an opening with parallel sides, a retainer cooperating with the support and holding the blade in place, said support having upstanding ears extending through the opening in the blade and affording guide means to constrain the blade to follow a straight-line path, an actuating roller rotatably mounted

on said ears and providing a cam portion, a projection extending inwardly from the side of the opening in the blade and engaging said cam portion to function as a follower therefor, said support having a generally semi-cylindrical part disposed below the roller and affording a recess in which the lower part of the roller is received, said semi-cylindrical part connecting portions of the support at opposite sides of the roller.

9. In a razor of the class described, a blade 10 support comprising a plate-like body portion having a central opening therein, opposite sides of said opening being connected by a generally curved shield portion, upstanding ears disposed at the ends of the opening, and a roller journaled 15 on the ears and having its lower part received in said shield portion.

10. In a razor of the class described, a support comprising a plate-like body portion having a central opening therein, integral upstanding ears 20 at the ends of the opening, a roller journaled on the ears, integral parts of said body portion being shaped to curve downwardly below the roller to afford a recess below the opening in which a part of the roller is received, and an integral boss for 25 connection to a handle, said boss and said integral parts being integrally connected to each other.

11. A razor of the class described comprising a blade holder, a blade having opposite parallel cutting edges and an actuating roller rotatably mounted on the holder and having a cam groove, said blade having a central opening in which a part of the roller is disposed and having similar projections extending into engagement with the 35 cam groove on opposite sides of the axis of rotation of the roller whereby the blade may be reciprocated in a path parallel to its cutting edges in response to rotation of the roller.

12. A razor of the class described comprising a 40 handle, a blade holder connected to the handle and symmetrically arranged in relation thereto, a cam roller symmetrically supported by the holder, a double-edged blade mounted on the holder and having a central opening with portions engaging 45 the roller to function as followers so that the blade may be reciprocated in response to rotation of the roller.

13. A razor of the class described comprising a handle, a support connected to the handle and 50 symmetrically arranged in relation thereto, a cam roller symmetrically supported by the support, a double-edged blade mounted on the support and having a central opening with portions engaging the roller to function as followers so that the 55 blade may be reciprocated in response to rotation of the roller, and a swinging retainer normally positioned to hold the blade on the support, said retainer having a central opening through which the roller is exposed for engagement with the 60 flesh of the user of the razor.

14. A razor of the class described comprising a blade holder providing upstanding ears, a cam roller rotatably mounted on said ears, a blade having a central opening in which the roller and 65 ears are disposed, said opening being shaped to provide a follower portion engaging the roller so that the blade is reciprocated when the roller is rotated, said opening providing edges engaging the ears so that the latter guide the blade in a 70 rectilinear path as it is being reciprocated.

15. A thin razor blade of the class described having opposite parallel straight cutting edges and having a central opening, the opening being of rectangular form with opposite sides parallel to 75

the respective cutting edges, said opening extending the major portion of the length of the blade, the intermediate parts of said opposite sides each being interrupted by a single relatively small inwardly extending lug, the lugs being similar and directly opposite each other, the sides being straight between the lugs and the ends of the

opening to engage parts of a blade holder so that the blade may be guided in a straight line reciprocating path, said blade being symmetrical relative to both its longitudinal and transverse central axes.

WINFRED T. PARKIN.
